UNITED STATES PATENT OFFICE.

WILLIAM W. DOTY, OF STATEN ISLAND, NEW YORK, ASSIGNOR OF ONE-HALF TO SIDNEY ROSENBAUM, OF NEW YORK, N. Y.

RESILIENT MEMBER.

Application filed November 3, 1922. Serial No. 598,721.

The invention relates to a novel type of resilient member which is adapted for various purposes; and may be employed, for example, in the construction of a bumper for 5 self-propelled vehicles, as well as an elastic support for vehicle bodies, cushion seats, or as a bed spring, etc.

The invention consists essentially of a member which may comprise a resilient, 10 flattened spring-steel wire or rod, or a band of resilient metal; and in accordance with the invention, the same has an end formed as a spiral which is attached at its center to a suitable supporting member.

15 The nature of the invention, however, will best be understood when described in connection with the accompanying drawings, in which—

20 Fig. 1 illustrates the improved resilient member embodied in a bumper for self-propelled vehicles.

Fig. 2 illustrates a form of resilient member suitable for use as a back rest.

25 Fig. 3 illustrates an underneath view of an arrangement suitable for supporting a cushion seat or mattress of a bed; and Fig. 4 is a vertical section therethru, taken on the line 4—4, Fig. 3.

30 Fig. 5 is a sectional view illustrating a modification in the seat support.

Fig. 6 is an end view illustrating the spring member applied as a resilient support for a vehicle.

35 Referring to the drawings, and more particularly to Fig. 1 thereof, 10 indicates suitable supporting members, such as horns projecting from the chassis of a self-propelled vehicle (not shown), and provided with an upturned outer end for supporting and 40 carrying the bumper. The latter consists of a one-piece member of flattened spring-steel wire or rod, or of a band of resilient metal. The intermediate impact receiving portion 11 is shown bent backwardly at the ends 45 which are then turned inwardly and follow for a short distance along and back of said impact portion 11, but are spaced therefrom. The remaining portions of the resilient metal, at each end, are then wound 50 into a spiral 12, as indicated, and lie substantially in the plane of said impact receiving portion with the inner ends suitably secured to the upturned portion of the respective horns or like members 10. It will

be observed that the spiral winding at one end is in the reverse direction from that at the other end. A force acting on the portion 11, between these two points of support as between y and y' , would thus tend to cause both end spiral portions to close the 60 springs at the top and open the same at the bottom to accommodate the impact or pressure; whereas a force applied to an end portion of the impact receiving portion 11 outwardly of either y or y' would tend to 65 cause the particular spiral at that end to close or wind up and the spiral at the other end to open or unwind. It is preferred, in some instances, to reinforce the portion 11 with one or more leaves 13.

70 This construction of resilient member is also particularly suitable as a spring back-rest frame, Fig. 2; and in that embodiment, the outer surface of the frame forming member 15 is bent to the desired shape, for example, into an arc of a circle. It is understood, of course, that the same may be variously formed.

75 The particular spiral arrangement of the spring-member may also serve to provide 80 a very satisfactory elastic support as a box spring or as a means for supporting a cushion or mattress 20 or the like, Figs. 3 and 4; and in such arrangement, a plurality of separated spring members are utilized and 85 arranged at right angles, as indicated, and preferably interwoven, the extensions from the spiral portions thereof providing a surface 21 to receive and support the weight 90 of the cushion 20 and may have end upturned portions 22 to afford a side support or retainer therefor, the said extensions, also, being curved or formed to accommodate the particular type of cushion or mattress employed. A rod or pipe frame 23 supports 95 the various spirals 24 at their respective centers, as shown.

As shown in Fig. 5, by having the convolution of the spirals 26 in the reverse direction from those indicated in the previously described embodiments, a rounded edge or surface 27 may be provided; and this will, in many instances, be found to be of advantage.

100 In Fig. 6, an arrangement is set forth in which the load receiving portion 30 is substantially horizontal; and such portion may afford a convenient and satisfactory sup-

port for a vehicle body 31, the ends of the spirals 32 of the support member being secured directly or indirectly to an axle 33 of the vehicle. The said supporting surface 30 of the spring is secured to the body 31 of the vehicle which, when provided thus both at the front and rear with the transverse support, is insured against undue shocks and side wobbling as blows will be quickly neutralized by the spring and equilibrium restored.

The novel resilient member herein described provides thus for a non-rigid, flexible and resilient support which, in the case of 15 a bumper, will serve to cushion an object struck and to reduce the impact on the vehicle. It will serve, furthermore, as a resilient support member for vehicle bodies and for cushions, mattresses, and the like; 20 and may be formed of any desired contour. Moreover, as a one-piece article, it is extremely simple and inexpensive to construct; and the spiral loop may consist of one or 25 more turns as will be found necessary for the desired degree of resiliency, the mass carried being always supported from the center of the spiral portion.

I claim:—

1. A resilient member comprising a strip 20 of resilient metal with each end bent into a spiral and the intermediate portion adapted to receive a load, and supporting means therefor secured to the spiral ends substantially at the centers thereof.

2. A resilient member consisting of a piece 35 of resilient material having a substantially straight portion, spirals formed of said piece of material adjacent to the ends of said straight portion and connected thereto, and supporting means for the spirals secured to the spirals at substantially the centers of the spirals.

3. A resilient member consisting of a piece 45 of resilient material having a substantially straight portion, spirals having a plurality of convolutions formed of said piece of material adjacent to the ends of said straight portion and connected thereto, and supporting means for the spirals secured to the spirals at substantially the centers of the spirals.

4. A resilient member consisting of a piece 55 of resilient material having a substantially straight portion, spirals formed of said piece of material adjacent to the ends of said straight portion and connected thereto in spaced relation to each other in a plane parallel to the plane of said straight portion, and supporting means for the spirals

secured to the spirals at substantially the 60 centers of the spirals.

5. A resilient member consisting of a piece of resilient material having a substantially straight portion, spirals formed of said piece of material adjacent to the ends of said 65 straight portion and connected thereto in spaced relation to each other in a plane parallel to the plane of said straight portion, and supporting means for the spirals secured to the spirals at substantially the 70 centers of the spirals, the ends of said straight portion being located outwardly from the points of intersection with said straight portion of straight lines from said supporting means to said straight portion. 75

6. A resilient member consisting of a piece of resilient material having a substantially straight portion, and spirals formed of said piece of material adjacent to the ends of said straight portion and connected thereto 80 in spaced relation to each other in a plane parallel to the plane of said straight portion, the portions of said piece connecting the spirals to said straight portion being 85

90 substantially U-shape.

7. A resilient member consisting of a piece of resilient material having a substantially straight portion, spirals formed of said piece of material adjacent to the ends of said straight portion and connected thereto in 95 spaced relation to each other in a plane parallel to the plane of said straight portion, the portions of said piece connecting the spirals to said straight portion being substantially U-shape, and supporting means for 95 the spirals secured to the spirals at substantially the centers of the spirals.

8. A resilient member consisting of a flat strip of resilient metal having a substantially straight portion, spirals formed of said strip 100 adjacent to the ends of said straight portion and connected thereto in spaced relation to each other in a plane parallel to the plane of said straight portion, the portions of said strip connecting the spirals to said straight portion 105 being of substantially U-shape, and supporting means for the spiral secured to the spirals at substantially the centers of the spirals, the ends of said straight portion being located outwardly from the points of 110 intersection with said straight portion of straight lines from said supporting means to said straight portion.

Signed at New York, in the county of New York and State of New York, this 115 31st day of October, A. D. 1922.

WILLIAM W. DOTY.
